(57) **CLAIM**

The ornamental design for a hip and ridge tile anchor, as shown and described.

DESCRIPTION

FIG. 1 is a top, front perspective view of a first embodiment of a hip and ridge tile anchor.

FIG. 2 is a front or rear view of the hip and ridge tile anchor of FIG. 1.

FIG. 3 is a side view of the hip and ridge tile anchor of FIG. 1.

FIG. 4 is a top view of the hip and ridge tile anchor of FIG. 1.

FIG. 5 is a bottom view of the hip and ridge tile anchor of FIG. 1.

FIG. 6 is a top, front perspective view of a second embodiment of a hip and ridge tile anchor.

FIG. 7 is a front or rear view of the hip and ridge tile anchor of FIG. 6.

FIG. 8 is a top, front perspective view of a third embodiment of a hip and ridge tile anchor.

FIG. 9 is a front or rear view of the hip and ridge tile anchor of FIG. 8.

FIG. 10 is a top, front perspective view of a fourth embodiment of a hip and ridge tile anchor.

FIG. 11 is a front or rear view of the hip and ridge tile anchor of FIG. 10.

FIG. 12 is a top, front perspective view of a fifth embodiment of a hip and ridge tile anchor.

FIG. 13 is a front or rear view of the hip and ridge tile anchor of FIG. 12.

FIG. 14 is a top, front perspective view of a sixth embodiment of a hip and ridge tile anchor; and,

FIG. 15 is a front or rear view of the hip and ridge tile anchor of FIG. 14.

The dash-dash jagged cut line of FIGS. 1 through 15 indicate that any portion of the hip and ridge tile anchor beyond what is shown forms no part of the claimed design.

1 Claim, 13 Drawing Sheets
